UNITED STATES PATENT OFFICE.

CHARLES H. ROBERTS, OF EVANSVILLE, INDIANA.

PORTABLE DERRICK.

No. 927,680.

Specification of Letters Patent.

Patented July 13, 1909.

Application filed February 10, 1909. Serial No. 477,160.

To all whom it may concern:

Be it known that I, CHARLES H. ROBERTS, a citizen of the United States, residing at Evansville, county of Vanderburg, and State 5 of Indiana, have invented certain new and useful Improvements in Portable Derricks, of which the following is a specification.

This invention relates to portable derricks.

10 The invention has for its object the provision of a derrick and vehicle associated in a novel manner, together with derrick operating means carried by the vehicle; a derrick of novel construction having improved means 15 for swinging the jib, improved means for supporting the mast, improved means for adjusting or extending the mast, and improved means for guiding the cables; and a derrick combined with a vehicle in a novel 20 fashion so as to be adapted to be readily attached to or removed therefrom, anchored when in use in order to remove the strain from the vehicle, and so constructed and arranged as to afford a convenient portable 25 structure which can be readily moved from place to place and rapidly and easily positioned and made ready for use in hoisting operations.

The invention is set forth fully hereinafter 30 and its novel features are recited in the appended claims.

In the accompanying drawings:—Figure 1 is a side elevation of my improved derrick in position with the traction engine; Fig. 2, a 35 front elevation of the same with the boom omitted; Fig. 3, an enlarged detail of the mast and boom, the former being shown in longitudinal section; Fig. 4, a detail cross-section on the line 4—4 of Fig. 3; Fig. 5, a detail perspective view of the upper portion of 40 the lower mast section; Fig. 6, a detail plan view of the turn-table; Fig. 7, a detail plan view, partly in section, showing the pulleys and cables connecting the boom with the engine; and Fig. 8, a detail side elevation of the 45 lower portion of the upper mast section.

Any vehicle can be employed in connection with the derrick constituting the present invention, but the structure preferably employs 50 braces the derrick and a suitable traction engine which combines power of locomotion with derrick operating means, and I, therefore, preferably use a traction engine 1 of approved form.

55 Secured to the front of the traction engine 1 are clamps 2 which rigidly secure a holder 3

having a fixed collar 4 on its lower end. Located loosely within the holder 3 is the lower mast section 5 whose lower end is seated in a shoe 6, which has a ball 7, received in a step 8 and provided with a ball bearing 9. The step 8 has a platform 10 provided with prongs or feet 11 adapted to be sunk into the earth to form a support for the mast and jib.

Mounted loosely on the holder 3 between the lower clamp 2 and the collar 4, is a turn-table 12, which has a grooved periphery and is provided with a radial slot 13 and arc-shaped slots 14.

The jib 15 has its lower end pivoted by king bolts 16 to ears on the shoe 6, said jib being provided with a guide 17 which is located in slot 13.

Secured to the holder 3 is a bracket 18 to which is journaled a drum 19 which carries a worm-wheel 20 in mesh with a worm 21 carried by said bracket 18. The drum 19 has cables 22 which pass through the slots 14 and are connected at 23 to the shoe 6, thus providing means whereby the entire mast, jib, step and platform may be elevated when it is desired to move the portable derrick to another position.

The upper section 24 of the mast telescopes within the lower section 5, being provided with a packed piston 25 snugly fitting the interior of said tubular section 5. At frequent intervals the mast section 24 is provided with sets of holes 26 and the mast section 24 carries a two-part clamp 27 having 90 dowels 28 which are adapted to be received in any of the sets of holes 26 so that upon suitable clamping of said clamp 27, the upper mast section 24 will be supported upon the lower mast section 5, but in order to securely connect the telescoping mast sections, I preferably provide the upper end of the section 5 with slots 29 and surround it with a clamp 30 which, on being tightened, draws the split upper end of mast section 5 tightly 100 around the lower end of mast section 24.

The mast section 5 serves as a steam cylinder for the piston 25 on mast section 24, steam being led to the interior of the lower part of the section 5 by a pipe 31 which is connected to the steam dome 32 of the traction engine and is controlled by a three-way valve 33 which is adapted, according to which way it is turned, to admit the steam from dome 32 to the interior of section 5 to 105 elevate the section 24, or, to release whatever pressure there may be in the section 5 to per-

mit the mast section 24 to be lowered to any desired extent. This construction and capacity for adjustment in no manner interferes with the elevation of the entire mast 5 within the holder 3 by using the gearing 20, 21, but it provides for adjustment of the mast to any desired height at any time, it being understood that the clamps 27 and 30 will be loosened and re-clamped, as occasion 10 may require, during such adjustment of the mast.

Carried on the vehicle 1 is any approved type of winding drums, specific description being unnecessary. These drums are driven by a shaft 34 which is belted to the engine. 15 This shaft carries a bevel gear 35 which is adapted to mesh with either one or the other of bevel gears 36 and 37 which are loosely splined to a vertical shaft 38, suitably journaled. The gears 36 and 37 are operated by independent levers and control the swinging of the jib. The shaft 38 operates gearing 39, in turn operating a drum 40, around which is wound a cable 41, which passes around and 20 is connected to the turn-table 12. According to which of the gears 36 or 37 is in mesh with gear 34, the turn-table 12 will be moved in one direction or the other and the jib similarly swung, regardless of its degree of elevation or depression. The drum 42 operates a 25 cable 43 which passes under a swiveled sheave 44 carried by mast section 24 and thence around suitable sheaves 45, 46, 47, thus controlling the elevation and lowering 30 of the jib 15.

The cables 48 for raising and lowering and operating the bucket 49 pass around suitable pulleys on the jib and onto the drums 50. These cables pass on opposite sides of the 40 smokestack and on opposite sides of a drum 51, which loosely turns on holder 3, being provided with interposed roller bearings 52 to minimize friction, said drum being interposed between upper and lower brackets 53 45 secured to holder 3. The brackets 53 also form a support for idler drums 54. Consequently, whether the jib be turned to the right or left, both cables 48 are running freely over idlers and thus any entangling of 50 said cables is prevented.

Having thus described my invention, what I claim as new and desire to secure by Letters Patent, is:—

1. In a portable derrick, the combination 55 with a motive-fluid operated traction engine or the like, of a derrick adapted to be carried thereby which is provided with a motive-fluid operated extensible mast, and means for utilizing the motive fluid of the engine for 60 extending the mast.

2. In a portable derrick, the combination 65 with a movable vehicle, of a derrick adapted to be carried thereby having a substantially vertically reciprocatable mast, and means for moving the mast up or down so that it may

be supported by the ground when in use or elevated to permit travel of the vehicle.

3. In a portable derrick, the combination with a movable vehicle, of a derrick, and means detachably securing the derrick to the 70 vehicle permitting it to be bodily removed from the vehicle.

4. In a portable derrick, the combination with a movable vehicle, of attaching devices secured to one end of the vehicle, and a derrick detachably held by said attaching devices. 75

5. In a portable derrick, the combination with a movable vehicle, of a mast carried thereby adapted to be raised or lowered, a 80 turn-table rotatable with the mast and which has openings, a jib operated by the turn-table, a drum above the turn-table, cables operated by the drum which pass through the openings aforesaid and are operatively 85 connected to the mast below the turn-table, and means for turning the turn-table.

6. In a portable derrick, the combination with a motor vehicle, of a derrick whose mast is connected to the vehicle, means for supporting the mast to relieve the motor vehicle from the weight thereof and of the load when in operation, power operated self-contained means carried by the motor vehicle for swinging the jib, and power operated means carried by the motor vehicle for operating the jib and its load. 90

7. In a derrick, a mast composed of telescoping sections, one of which has openings, in combination with a releasable clamp 100 adapted to embrace the section having openings, said clamp having dowels or pins adapted to enter said openings and being engageable with the other of the telescoping sections. 105

8. In a derrick, the combination with a mast and a jib, of a loose drum arranged concentrically of the mast, and cables disposed on opposite sides of said drum which run to the jib. 110

9. In a derrick, the combination with a support, of a holder attached thereto, a mast adjustable up and down in said holder, means for adjusting said mast up and down in said holder, said mast having an extensible part, and means for adjusting said extensible part of the mast. 115

10. In a derrick, the combination with a support, of a holder attached thereto, a mast adjustable up and down in said holder, means for adjusting said mast up and down in said holder, said mast being composed of telescoping sections, one acting as a cylinder and the other as a piston, and means for controlling the supply of motive fluid pressure 120 to the cylinder of said extensible mast.

11. In a derrick, the combination with a support and a mast holder, of a mast adjustable in said holder whereby it may be positioned at different heights, a jib, a turn-table 125 130

which is loose in relation to the adjustable mast, said jib being operated by the turn-table, and means for turning said turn-table.

12. In a derrick, the combination with a support, of a mast holder, a mast adjustable in said holder, a turn-table loosely encircling the mast and provided with openings, a jib carried by the mast and operated by the turn-table; and means for raising and lowering the mast comprising operating mechanism located above the turn-table and cables operated by said operating mechanism which pass through the openings in the turn-table and are connected to the mast.
- 10 13. In a portable derrick, the combination

with a vehicle and a winding drum carried by said vehicle, of a mast carried by said vehicle, a jib carried by the mast, means for swinging the jib, an idler drum or pulley loosely encircling the mast, idlers positioned on opposite sides of said idler drum or pulley, and cables running from the drum carried by the vehicle which pass on opposite sides of the idler drum or pulley and thence to the jib.

20 In testimony whereof, I hereunto affix my signature in presence of two witnesses.
